UNITED STATES PATENT OFFICE

HARRY A. DOUGLAS, OF BRONSON, MICHIGAN

IGNITER

Application filed May 9, 1929. Serial No. 361,674.

My invention relates to igniters, the igniter of my invention being of the class disclosed in my copending applications Serial Nos. 361,671; 361,672 and 361,673, each filed 5 May 9, 1929. In each structure of the aforesaid copending applications a casing is employed having a lid thereon which carries the sparking mechanism which is inclusive of a striker and a body of pyrophoric material 10 from which sparks may emanate, this body of pyrophoric material being located within the region of an inflammable element, such as a wick which projects into a fuel receptacle. Each such sparking mechanism is inclusive of a lever carried by the lid and connected with the striker, a spring for operating the lever and a latch for maintaining the lever in a depressed position against the force of the spring. When the latch is released to permit the spring to operate the lever to cause the spark the lever opens the top portion of the lid, so that the lid does not then fully enclose the sparking mechanism. In accordance with my present invention the 15 lever is in the form of a hood which encloses the lid and, apparently, forms the lid of the casing, so that the mechanism within the lid proper is guarded by the lid and the lid also may serve as a windshield to protect the flame that results from the operation of the 20 sparking mechanism. The wick or inflammable element is supplied with fuel from a suitable member, such as a fuel container, which is removable from the casing, this fuel 25 container being held in place by the lid.

The invention will be more fully explained in connection with the accompanying drawings in which Fig. 1 is a view of an upper portion of the igniter of my invention, parts 30 being shown in sectional elevation and parts in full elevation, this figure being generally taken on line 1—1 of Fig. 2; Fig. 2 is a sectional view on line 2—2 of Fig. 1; Fig. 3 is a sectional view on line 3—3 of Fig. 1; Fig. 4 is 35 a side view with parts broken away; Fig. 5 is a plan view; Fig. 6 is an end view of an upper portion of the structure; Fig. 7 is a view generally taken on line 7—7 of Fig. 1; Fig. 8 is a sectional view on line 8—8 of Fig. 1; Fig. 50 9 is a sectional view on line 9—9 of Fig. 1;

Fig. 10 is a view, in elevation, of the preferred form of fuel member, parts being broken away and shown in section; and Fig. 11 is a sectional view on line 11—11 of Fig. 1. The fuel member illustrated is inclusive of 55 a container 1 for the liquid fuel 2. This container has a cover 3 permanently secured thereto. This cover is furnished with an interiorly threaded bushing 4 that passes through an opening in the cover and receives a threaded closure plug. This closure plug has a flange 6 which presses a sealing gasket 7 upon the bushing. Fuel is admitted to the container through the opening occupied by the plug. Fuel is discharged from the container by means of a wick 8 that reaches the bottom of the container and passes through another opening in the cover 3, this latter opening receiving a bushing 10 through which the wick passes. An upright elongated bushing 11 has its lower end clinched into the border of the bushing 10 that surrounds an opening at the upper end of this bushing. The part 11 snugly surrounds the upper end of the wick to position it sufficiently close to the spark emanating portion of the igniting mechanism. When containers of the construction described are carried in stock, each is supplied with a cap 12 whose skirt snugly engages the bushing 10 to guard 70 against the escape of liquid fuel. 75

When the container is inserted within the body 13 of the casing of an igniter the cap 12 is removed, this cap being replaced by a snuffer 14 that is placed in sealing engagement with the bushing 10 when the igniter is not in use and which is removed from such engagement when the wick is to be lighted, as will more fully hereinafter appear. The casing also includes a retainer 15 which is 80 preferably in the form of a lid for and preferably hinged upon the casing body. Said lid is somewhat in the form of an inverted cup whose bottom edge or rim is tightly received within the upper end of the casing body, this 85 rim then engaging the bead 17 which is formed upon and about the upper end of the fuel container, said lid then preventing the casing from being displaced upwardly. A leaf spring 18 is secured, at one end, within the 90 95 100

casing body and upon its bottom wall, this spring being depressed by the lid, when closed, through the intermediation of the fuel container to prevent the fuel container from moving about within the casing, the spring 5 compensating for some inequalities that may occur in manufacture. When the fuel container within the casing is to be replaced the lid is swung back from the casing body.

10 The retainer or lid 15 desirably constitutes a carrier for all of the parts of the igniting mechanism, though the invention is not to be thus limited. The igniting mechanism illustrated is inclusive of a block 19 of friable material, preferably flint, which is normally 15 substantially stationary with respect to the container and the wick or inflammable element 8 where it issues from the container. This relationship of this block and the wick is desirably normally maintained by placing the block within a vertically disposed socket 20 which is rigidly assembled with the lid. The igniting mechanism also includes a 20 striker 21 which is preferably in the form of a striking wheel 21. This striking wheel has an elongated hub which is journaled upon a shaft 21' which is removably secured to the lid. This hub also carries a pinion 21² which is turned in order to turn the striking wheel 25 to create sparks. The rack bar 22 is in mesh with the pinion. This rack bar is moved to the right when the igniter is used for its purpose, the striking wheel then grinding out sparks from the body 19. It is guided in its 30 movement, at its right hand end, by the spring 23 which maintains it in mesh with the pinion. A leaf spring 25 is anchored, at one end, to the cover 15 and presses, at its 35 unmounted end, against the block 19 to maintain the block in engagement with the striking wheel and to feed the block through the socket 20 as the block becomes worn by said wheel. The unmounted end of springs 25 may be moved out of alignment with block 40 19, when it is desired to replace this block. The rack bar 22 is pivotally mounted at 45 upon the lever 27. This lever is pivoted upon the lid at 28 at which place the lid is also hinged upon the casing body. The lever 50 27 is also in the form of an inverted cup or hood that encloses the lid and imparts a finished appearance to the device as indicated in Fig. 4.

A coiled spring 29 is anchored, at its left 55 hand end, to a bracket upon the lid 15 and at its right hand end is connected with a latch 60 that projects through an opening 31 in the front end of the lever 27. The inner end of the latch has rocking engagement, at 65 30', with the shelf 32 which is fixed upon and within the lid 15 and on which shelf the socket 20 is carried. The spring 29 normally 70 serves to place the projecting end of the latch above the ear 27' upon the lever to hold 75 this lever down against the force of a spring

80 33. This spring surrounds the rack bar 22 and is bottomed at its left hand end against the bracket formation 22' which is carried by the lever 27 and upon which the rack bar is directly pivoted. The right hand end of the 85 spring 33 engages the bracket formation 15² that is carried by and within the lid 15. When the latch 31 is moved to the left to clear the ear 27' the lever is moved in a 90 counterclockwise direction by the spring 33 due to the expansion of this spring and the movement of its left hand end toward the left. During this counterclockwise movement of the spring 33 the rack bar 22 turns the pinion 21² and the striking or grinding 95 wheel 21 to cause sparks to emanate from the block 19. These sparks pass through the opening 15³ against the top of the wick 8 from which the snuffer 14 has been moved, this snuffer traveling with the lever. The 100 right hand end wall of the lid 15 terminates to the left of the wick and between the wick and the block of spark producing material 19. The wick is thus exposed when the lever 105 27 is lifted, but at the same time the portion of the lid 15 between the wick and the block 19, serves as a windshield to protect the flame at the wick. The extent to which the lever 27 may be opened is limited by the pin 34 upon one side of the rack bar and a marginal portion of the opening in the part 15² 110 through which the rack bar 22 passes.

Changes may be made without departing from the invention.

Having thus described my invention, I 100 claim:

1. An igniter including a body casing having outer and inner lid members hinged thereto for pivotal movement on a common axis, a bracket fixed to the outer lid and extending through an opening in the inner lid, a releasable latch for holding the outer lid closed, a sparking mechanism operating bar pivoted at one end to said bracket and having its other end extending through an opening in the inner lid, spring means operable when the latch is released to cause the outer lid to swing on its hinge and reciprocate the operating bar, a sparking mechanism within the inner lid operated by the aforesaid movement of the operating bar to produce sparks adapted to pass through an opening in the inner lid, and an inflammable element exteriorly of the inner lid and adjacent the last named opening to receive igniting sparks 110 from the sparking mechanism.

2. An igniter including a body casing having hinged outer and inner lid members, a releasable latch for holding the outer lid closed, a sparking mechanism operating bar pivoted at one end to the outer lid through an opening in the inner lid and having its other end slidably engaged through a second opening in the inner lid, spring means operable when the latch is released to cause the 125

outer lid to swing on its hinge and reciprocate the operating bar, a sparking mechanism within the inner lid operated by the aforesaid movement of the operating bar to produce sparks adapted to pass through an opening in the inner lid, and an inflammable element exteriorly of the inner lid and adjacent the last named opening to receive igniting sparks from the sparking mechanism.

10 In witness whereof, I hereunto subscribe my name.

HARRY A. DOUGLAS.
